UNITED STATES PATENT OFFICE.

PETER SWANSON, OF SOUDAN, MINNESOTA.

AUXILIARY CAR-STEP.

1,353,364.

Specification of Letters Patent. Patented Sept. 21, 1920.

Application filed February 2, 1920. Serial No. 355,882.

To all whom it may concern:

Be it known that I, PETER SWANSON, a citizen of the United States, residing at Soudan, in the county of St. Louis and State of Minnesota, have invented certain new and useful Improvements in Auxiliary Car-Steps, of which the following is a specification, reference being had therein to the accompanying drawing.

10 My invention relates to auxiliary steps for railway car platforms and the principal object of the present invention is to provide an improvement upon the steps now in use, constructed upon somewhat similar lines though having the objectionable feature of failing to function at times when the supporting mechanism of the step happens to be left unlocked and which failure is apt to result in serious accident to one 15 in the act of using the step.

Other objects and advantages of the peculiar construction will appear in the further description of the invention.

Referring to the accompanying drawings 25 forming a part of this application and in which like reference characters indicate like parts:

Figure 1 represents a rear elevation of the auxiliary step and its supporting mechanism as applied to the stationary platform step of a car, and

Fig. 2 is a broken side elevation of same showing the step extended for use, and in dotted lines, its position when folded.

35 1 represent the side walls of the stationary steps of a car to which the auxiliary step 2 is pivotally suspended by the metal straps 3—3 they being pivotally attached as at 4 to the sides of the stationary steps 5 in any 40 desired manner. The step 2 is rigidly fixed to two supporting arms 6—6 which are substantially in line with and extend rearwardly a distance approximately twice the depth of the step, where they are suspended 45 upon depending crank arms 7—7 mounted upon the cross shaft 8. This shaft is preferably square in cross section and the crank arms are provided with suitable hubs 9 for secure mounting upon said shaft.

50 In a convenient location near the top of the fixed steps 5, upon one side thereof and accessible for operating the auxiliary step is mounted upon the stub shaft or pin 10 the hand lever 11, there being a suitable 55 quadrant 12 in cooperative engagement with

the lever and a spring latch 13, as is common in such structures. Extending forward from the shaft or pivotal support 10 and preferably as an integral portion of the lever 11 is the crank arm 14 which upon its 60 free end pivotally supports the link 15, the latter at its opposite end being suitably attached to the free end of the crank arm 16 mounted upon the cross shaft 8 and by which the latter is rocked for actuating the 65 step. This latterly described arrangement of levers is mounted externally of the side of the fixed steps so as to be conveniently out of the way.

From the foregoing it is evident that the 70 natural tendency of the auxiliary step and its immediate connections is to remain depressed and in active position while the toggle connection intermediate of the cross shaft 8 and the operating lever impart an 75 opposite tendency thus nicely balancing the complete mechanism slightly in favor of the step remaining in extended position, so that the operation of the device is exceedingly simple and easy of accomplishment. 80

The lower ends of the crank arms 7 are provided with straight shoulders 17 formed at right angles thereto and which abut the straight horizontal face of each arm 6 when the arms are in their lowermost position, 85 thus abruptly terminating the opening action of the connection between the arms 6 and 7 and insuring the positive positioning of the auxiliary step while in action so that it cannot swing back and forth.

To further stabilize the position of the step I prefer to position the pivotal points 4 of the straps 3 slightly in advance of their connection with the step when the latter is fully extended, thus insuring a constant tendency of the step to lower and advance, which will effectually counteract any opposite tendency when a weight is applied to the step whether it is locked or not and which opposite tendency has proven dangerous in other forms of steps as before stated. 95

What I claim is:

1. The combination with the platform steps of a railway car having an auxiliary step pivotally suspended upon depending 105 straps below the lowermost stationary step, of the pivotal connection of the lowermost end of the straps to the auxiliary step being inwardly of the pivotal connection of the uppermost end of the straps to the sta- 110

tionary steps when the auxiliary step is in extended position substantially as and for the purpose described.

2. The combination with the platform 5 steps of a railway car having an auxiliary step pivotally suspended below the lowermost stationary step, of straps depending from the stationary steps and pivotally supporting the auxiliary step, the pivotal connection of said straps to the stationary steps being outwardly of the pivotal connection of said straps to the auxiliary step when in 16 fully extended position; a shaft installed beneath the stationary steps, arms rigidly

fixed to and extending inwardly of the auxiliary step, arms extending downwardly from the shaft and pivotally connected to the first mentioned arms, means at such connection whereby to limit the forward movement of the auxiliary step and means for 20 manually locking the shaft, substantially as described.

In testimony whereof I hereunto affix my signature in the presence of two witnesses.

PETER SWANSON.
